RESILIENT CAP AND CONTAINER CLOSED
THEREBYCharles J. Jesnig, Florida Park, Pa., assignor to
Package Devices, Inc., Philadelphia, Pa., a cor-
poration of Pennsylvania

Application May 12, 1948, Serial No. 26,687

1 Claim. (Cl. 215—38)

1 The present invention relates to resilient caps of the character which surround and engage over the mouth of a container, and to containers suited for use therewith.

A purpose of the invention is to provide a resilient plastic cap having inner and outer rings one surrounding another and spaced from one another at the gripping end.

A further purpose is to provide a resilient plastic cap which will hold firmly on the mouth of a container having relatively low side wall tolerance, without exerting undue force or running the risk of breaking the container.

A further purpose is to provide a gripping ring on the side wall of a cap within an outer ring, and desirably to employ a bead on the interior of the gripping ring, with or without a cooperative bead on the exterior of the mouth of the container.

A further purpose is to grip by a portion on the cap having relatively smaller inside diameter which is separated from the surrounding side wall by an annular groove.

A further purpose is to provide an abrupt face toward the end wall on the gripping ring.

A further purpose is to interrupt the circumference of the gripping ring.

A further purpose is to make the outside of the side wall generally straight, with the outside diameter of the outer ring extending in prolongation of the portion of the side wall adjoining the end wall.

A further purpose is to provide a closure which can be made effectively from polyethylene and the like.

Further purposes appear in the specification and in the claim.

In the drawings I have chosen to illustrate a few only of the various embodiments in which my invention may appear, choosing the forms shown from the standpoints of convenience in illustration, satisfactory operation and clear demonstration of the principles involved.

Figure 1 is a perspective of one form of cap embodying the principles of the invention.

Figure 2 is a fragmentary perspective of a container to which the cap is adapted to be applied.

Figure 3 is a bottom plan view of the cap of Figure 1.

Figure 4 is a fragmentary section of Figure 3 on the line 4—4.

Figure 5 is a view corresponding to Figure 4, except that it is sectioned on the line 5—5 of Figure 3, and showing the cap applied to a straight ended container.

Figure 6 is a bottom plan view of a variation in the cap of the present invention.

2

Figure 7 is a view corresponding to Figure 5 showing a variant form of container mouth.

Figure 8 is a view corresponding to Figures 4 and 5 showing the invention applied to a dispensing closure.

Figure 9 is a central vertical section of a container mouth and variant form of cap in accordance with the invention.

Figure 10 is an enlarged fragment of Figure 9. Describing in illustration but not in limitation and referring to the drawings:

In the present practice, numerous small bottles, vials, cans and other containers are closed by internal plugs, corks, or the like, which are used with indifferent success because the tolerance on the mouth of the container, particularly when made of glass, is very wide and often the inside or outside diameter may vary between the maximum and minimum limits by as much as 0.020

inch. If the internal closure is designed to provide adequate tightness of fit under conditions of maximum internal diameter, it is likely to be too tight under conditions of minimum internal diameter, and the result has been frequent failure of containers due to splitting under the bursting force applied by the closure. Furthermore in non-porous plastics, a tight plug when applied to a liquid container is likely to compress air and fail to retain its seat.

The difficulties inherent in the manufacture of such internal plugs have interfered with the application of resilient plastics to closures of the type under discussion, notwithstanding that the properties of such plastics admirably suit them to

this service from other standpoints. A particularly desirable form of plastic for this purpose is polyethylene, which is quite impervious to moisture and various common gases, and is quite inert and safe in contact with pharmaceutical

products, foods and the like. This material is, however, comparatively stiff, and is likely to give trouble through bursting when used in internal

plugs.

In accordance with the present invention, a cap is provided for gripping the outside of the mouth of a container, in which the gripping action is provided by an internal gripping ring

forming part of the side wall, which is separate from a surrounding outer ring, thus assuring adequate resiliency of the gripping ring itself

while at the same time permitting sufficient thickness in the side wall.

The cap of the present invention is best suited for manufacture from a resilient plastic of the character of polyethylene, but it can less desirably be manufactured from other resilient plastic

materials, such as polyvinyl chloride, polyvinyl

chloride-acetate, and natural and synthetic rubber (including Buna S, Buna N, neoprene and Thiokol).

As shown in the drawings, the cap comprises an end wall 20 which may be of any suitable shape and is illustrated as a flat transverse disc-like closure in various forms, except for the form of Figure 8, in which it is shown as a dispensing end having an opening 21 suitably threaded at 22 and receiving a separate cap 23 conveniently internally threaded at 24.

Joined to the end wall at the circumferential edge and normally integral with it is a side wall, skirt or flange 25 which is suitably annular to conform with the shape of the mouth of the container and may in its upper portion adjoining the end wall be quite thick as shown at 26, so as to give considerable rigidity to the edge. At the end of the side wall opposite from the end wall, the side wall is separated by an annular groove 27 extending for a suitable distance through the length of the side wall, in the preferred embodiment about one-third or one-fourth of such length, but varying widely in different forms, so as to provide an inner gripping ring 28 and an outer gripping ring 29 separated by the groove 27. The thickness of the inner ring 28 will depend upon the desired gripping force and the inner ring 28 will be thin if such gripping force is to be slight and will be thick if such gripping force is to be great. It will be noted, however, that the presence of the annular groove 27 makes it possible to provide such gripping force independently of the desired thickness of the side wall.

The interior of the inner gripping ring 28 will preferably be provided with an inner bead 30 which will cause an inward extension of the lower effective end of the inner gripping ring 28 beyond the inner line of the side wall so as to concentrate the gripping force on a small area.

While the inner bead 30 is desirable, advantage may be obtained from the invention without employing this feature.

In operation the cap is forced down over the outside 31 of the mouth 32 of a suitable container such as a bottle or vial 33, causing the inner gripping ring 28 to expand as shown in Figure 5 into the space of the groove 27 and causing the interior bead 30 to hug the outside of the container. The snap action can be made very much more effective by providing a bead 34 (Figures 2, 7, 9 and 10) on the outside of the mouth of the container, and such a bead is normally present in any case in many glass containers due to the tendency (probably due to surface tension) of the softened glass to form a configuration having a round cross section. Thus as shown in Figure 7 the cap of the invention will snap on by expanding the gripping ring 28 and bead 30 on the cap until the bead 30 on the cap rides over the bead 34 on the mouth of the container, thus firmly locking the cap in place.

Also as shown in Figure 7, the slot has been deepened to facilitate the removal of the molded parts from the mandrel, and to impart greater resilience in use.

Where liquids are contained in the container it is preferable to use an unbroken gripping ring as shown in Figure 6, but where dry materials such as tablets or the like which are not especially hygroscopic are being contained, increased resiliency may be imparted to the gripping ring by breaking or perforating the gripping ring and bead at 35 at suitable points around the circum-

ference, so as to permit greater flexing of the gripping bead and gripping ring.

As shown in Figures 9 and 10, the side wall may have a larger interior diameter at 36 near the end wall to provide an annular recess to receive the bead 34 on the outside of the mouth of the container, and may have near the end of the side wall remote from the end wall a ring or portion of smaller internal diameter 30' which locks behind the external bead on the container mouth. The portion 30' will preferably be straight in internal cross section at 37 and will preferably have an abrupt change in diameter on the face 38 facing the end wall. The face 38 at its inner end engages the bead on the container. The outside ring 29 may be externally flared at 29' at the lower end.

It will be evident that in accordance with the invention the force applied in holding the cap on the container will be directly inwardly so that there will be no tendency to burst the container by a bulging force as has been present in the prior art internal plugs.

Experience has shown that the improved closure of the present invention can be applied and removed more reliably than the plugs, and will assure quick and easy removal and replacement even when the user does not apply special attention to the operation.

It will be evident that the capping of liquids in glass vials or the like is very easy because there is no plug intrusion into the container and no appreciable air compression in capping according to the invention.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claim.

Having thus described my invention what I claim as new and desire to secure by Letters Patent is:

In a container, a vessel having a neck provided with an exterior endless annular neck ring extending out radially beyond the adjoining portion of the neck, and a polyethylene cap having an end portion closing the otherwise open end of the neck and sealing against the end of the neck, and an integral endless annular side wall connected to the end portion and extending around the outside of the neck ring and beyond the neck ring away from the end of the neck, the side wall including an endless annular interior flange integral with the rest of the side wall, separated from the portion outside by an open groove free from occupancy by any container wall and extending from the end of the side wall toward the end of the neck ring, joined to the rest of the side wall at the outside of the inner flange and at a position toward the end of the neck with respect to the end of the side wall, the inner flange engaging the neck ring on the side of the neck ring remote from the end of the neck, and an outer flange outside the inner flange and extending to the end of the inner flange, the groove allowing the inner flange inside the groove to expand and contact during application and removal of the cap independently of the outer flange.

CHARLES J. JESNIG.
